LEWIS FERRY MOODY, OF PHILADELPHIA, PENNSYLVANIA

DRAFT TUBE

Application filed February 28, 1928. Serial No. 257,615.

This invention relates to hydraulic apparatus and more particularly to draft tubes of hydraulic turbines, and has for certain of its objects to provide not only an improved relation between the entrance, transition and discharge passages of the draft tube, but also to provide improved and simplified forms of these passages, whereby desirable characteristics of both the elbow and spreading types 10 of draft tubes are had, thus obtaining efficient deceleration of, and regain of whirl energy in, the fluid while turning and conducting the same from the turbine runner in a relatively small vertical and lateral space. 15 More specific objects are to offset the entrance or primal passage with respect to the longitudinal axis of the discharge passage and also to dispose the entrance passage well upstream with respect to the transition passage so that the upstream wall of the latter intersects and shortens the upstream side of the bell-mouth of the entrance passage, the bell-mouth otherwise being a surface of revolution. 20 Other objects and advantages will be apparent from the following description of the accompanying drawings, in which

Fig. 1 is a vertical sectional view of my improved draft tube shown in connection with a high specific speed propeller type turbine,

Fig. 2 is a fragmentary vertical section of a Francis type turbine runner and associated parts which can be substituted for the propeller runner shown in Fig. 1,

Fig. 3 is a slightly reduced sectional view on line 3-3 of Fig. 1,

Figs. 4, 5 and 6 are transverse sections taken on their respective lines on Fig. 1, and diagrammatically showing further sections,

Fig. 7 is a horizontal section looking upwardly toward the bell-mouth portion of the entrance passage, taken substantially on line 7-7 of Fig. 1,

Fig. 8 is a diagrammatic perspective view of the transition and discharge passages with the roof omitted,

Fig. 9 is a vertical sectional view of a modified turbine arrangement with my improved draft tube modified for use therewith,

Fig. 10 is a transverse section taken substantially on line 10-10 of Fig. 9,

Fig. 11 is a further modification of the draft-tube construction for use with a turbine arrangement similar to that shown in Fig. 9,

Fig. 12 is a transverse section taken on the line 12-12 of Fig. 11,

Fig. 13 is a further modified turbine arrangement and draft-tube construction embodying my invention,

Fig. 14 is a section taken substantially on the line 14-14 of Fig. 13,

Fig. 15 is an outline of a horizontal section showing a further modification of the draft tube,

Fig. 16 is a vertical section taken substantially on the line 16-16 of Fig. 15,

Fig. 17 is a diagrammatic view showing various sections taken on Fig. 15,

Fig. 18 is a graph showing the relation of Figs. 15 and 17 to an equivalent conical tube.

The illustrated embodiment of my invention is shown in connection with a high specific speed hydraulic turbine generally indicated by 1 wherein the flow passing to the runner 2, from a volute casing 3, is whirled by usual stay and guide vanes 4 and 5. The water is discharged from the runner into my improved form of draft tube having substantially three elements, comprising an entrance or primary passage, and transition and discharge passages. The latter two passages comprise in general a horizontal passage, considering the draft tube in the position shown in Fig. 1, although in other positions of the draft tube, the so-called horizontal passage may be in a vertical position with the entrance portion horizontal.

The entrance passage 6 is in the Fig. 1 form, slightly flaring for a substantial distance from its beginning near the runner 2, terminating in a greater degree of flare so as to form a bell-mouth 7. With the exception of a small upstream portion which is cut away, the bell-mouth, like the remainder of the entrance passage, is a surface of revolution, the flare on the bell being varied in accordance with the particular conditions under which the turbine is designed to operate. The bell is specifically shown as having a ra-

dius of curvature 8, the locus for the inner end of the radius being substantially a semi-circular line 9 coaxial to the entrance passage 6. The lowermost portion of the bell forms 5 a circular crest at the outlet of the entrance passage 6, which crest for the most of its circumference is of uniform distance from the beginning of the entrance passage.

As shown in Fig. 3, the axis of the entrance 10 passage is offset with respect to the central longitudinal axis of the discharge and transition passages 10 and 11, respectively, while a throat section 12 generally marks the line of division between the transition and discharge 15 passages. The floor 13 of the discharge passage extends in an upstream direction to form a curved upstream wall 14 of transition space 11, it being noted in Fig. 1 that the relatively large radius of curvature 20 of this upstream wall is such that it forms a smooth continuation of the upstream wall portion of the entrance portion 6, while the downstream side of the bell-mouth 7 curves smoothly but somewhat more sharply into 25 the roof 15, which flares upwardly in the downstream direction. Thus, the inner and outer walls of the draft tube as shown in Fig. 1 are generally similar to the elbow type of draft tube, although there is present 30 the bell-mouth 7 which by flaring laterally and also somewhat upstream gives characteristics of the spreading type of draft tube especially in connection with the lateral form of the transition space.

35 Further characteristics of the transition space are probably more readily seen by considering Figs. 3, 7 and 8, where it will be noted that portion 18 of the wall is a long, gradual curve merging into a rather short 40 curve 19. The upstream wall of the transition passage extending down from the lines 18 and 19 is formed by two series of radii, each disposed in planes remaining at all 45 times parallel to each other and to a plane which contains the axis of the entrance passage and is parallel to the axis of the discharge passage or vice versa. The loci for the radii centers are lines 20 and 21, which are substantially in the same form as the 50 combined curves 18 and 19, the locus 21 being used for the radius 22 forming the uppermost portion of the wall 14, while the locus 20 is for the radius 23 forming the lower half of wall 14. Hence if the transition 55 space is cut by any number of planes parallel to the axis of both the entrance and discharge passages of the draft tube the curvature of wall 14 would be the same in each case. The result of this construction is that 60 a relatively simple form of horizontal passage is created, the side walls of which are vertical and extend back to a point where the wall 14 blends therewith, thus causing the upstream wall 14 as shown in Fig. 8 to 65 have somewhat of a scoop-shape of simple

curved form. By having the entrance passage 6 disposed well upstream with respect to the transition space, the wall 14 intersects the upstream side of the bell 7 so as to create what appears to be a line of demarcation 24, 70 which however is a smooth curve blending the bell 7 with the upstream portion of roof 15 and surface 14. As shown by the shaded lines in Fig. 7 surrounding the entrance passage 6, the bell-mouth is merely intersected along its upstream side by the wall 14, which connects the entrance passage 6 and floor 13 in a long, smooth curve.

Further characteristics of the horizontal passage are, that the roof 15 in transverse section such as shown in Figs. 4 to 6 curves upwardly to a point indicated by the line 16, which is the side of the discharge and transition passages most remote from the turbine axis, the roof adjacent to the other side of these 85 passages remaining flat as shown in Fig. 6. This is conducive to efficient regain of the whirl energy inasmuch as the direction of whirl will be clockwise, looking down upon Fig. 3. A pier 17 is disposed in the central 90 portion of the discharge passage which not only supports the roof 15 and any superstructure, but also separates the discharge passage into two portions, which facilitates deceleration if the flow tends to have portions 95 of different velocities.

Various sections of the draft tube resulting from the above construction are shown in Figs. 4 and 5 by the lines lettered *aa*, *bb*, and *cc*, taken respectively on similarly lettered section lines in Fig. 7. The dotted line 25 is the outline of a section taken on line 5*a*—5*a* of Fig. 1, whereas the outline 26 represents the section taken on line 5—5 of Fig. 1, while the outlines 27 and 28 represent those 105 sections taken respectively substantially at the throat 12 and the outlet of the discharge passage 10.

In the form shown in Fig. 9 a horizontal double runner turbine is shown, from which the fluid is discharged into a draft-tube construction comprising in effect two draft tubes of the type shown in Fig. 1 placed together with the axes of the entrance passages in alignment, and having the discharge passages extending in the same direction and placed in juxtaposition but without having therebetween any structure corresponding to the floor 13. The draft tubes being so placed together will, of course, be of a right- and left-hand nature, so that the entrance passages 6 may be in alignment and at the same time have the discharge passages match. As shown in Fig. 9 the entrance passage 30 leading from each runner 31 is somewhat shortened in comparison with the one shown in Fig. 1, but in all other respects the same general construction of the other types is employed, both as to the entrance passage and the manner in which it blends with the up- 130

stream wall 32 of the transition spaces 33, the elements 32 and 33 corresponding in all respects with the wall 14 and passage 11. A further distinction over the preferred form is that the walls 32 terminate in a straight edge 32' thereby eliminating any surface corresponding to the floor 13 which would otherwise continue on down through discharge passage 34. In this modification the discharge passage instead of being horizontal is here shown as being in a vertical position, but this is merely a matter of relative positioning for even the construction as shown in Fig. 9 might be so disposed that the passage 34 would be horizontal. The discharge passage 34 preferably retains all of those characteristics and shapes shown in Fig. 1 and the various sections thereof.

In the Fig. 11 modification the upstream wall 32 is eliminated and a straight upper wall 35 provided, the draft tube construction in every other way remaining similar to that shown in Fig. 9. In Fig. 11 water flowing from the entrance passages 36 will meet and merge approximately at the center of the transition passage 37, and will flow into the discharge passage 38, which with the transition space 37 is offset in a manner as shown in Fig. 12.

In the modification of Fig. 13 the draft tube arrangement of Fig. 11 is embodied in a double-runner vertical setting, the fluid to which flows from an intake 39 to upper and lower runners 40 and 41. These runners, as disclosed in my copending application, Serial Number 195,105, filed May 28, 1927, of which this present application forms a continuation in part, are of different specific speeds. The fluid to each runner is whirled by the usual stay vanes or wicket gates 42 and 43, respectively. The discharge passage 44 curves downwardly instead of being straight, as in the other forms shown, but the other characteristics are somewhat the same in that, as shown in Fig. 14, the entrance passages 45 and 46 are offset with respect to the common transition space or passage 47, it being noted that the walls of the transition space are generally curved in a manner similar to that shown in the other forms.

In the modification of Fig. 15, entrance passage 50 is not only offset with respect to the horizontal passage, but the upstream wall of the latter is in a spiral form commencing at a laterally disposed point 51, it being understood that the bell 52 extends as far as possible in every direction so as to be a complete surface of revolution except where it is cut off by the intersecting upstream wall of the horizontal passage. The upstream wall in this form is substantially vertical along its entire length somewhat as shown at 53 in Fig. 16. Various vertical half sections radiating from the axis *d* of the entrance passage are shown in Fig. 17 by the

lines *e* to *m*, the various sections being taken on similarly lettered lines in Fig. 15. The roof 54 flares upwardly in the downstream direction as in the prior forms, although in transverse section the roof is straight across instead of sloping upwardly as in the preferred form. It will, of course, be understood that instead of sloping the roof upwardly in the downstream direction, the floor 55 may be sloped downwardly, leaving the roof horizontal, this also being applicable to the other forms.

Fig. 18 shows a line representing one side of a simple conical tube equivalent to all forms of the draft tube herein described, it being noted that as the fluid enters the bend of the tube there is an increase in the rate of deceleration, while in passing through the latter stages of the bend there is a decrease in the rate of deceleration which is followed in the discharge passage by an increase in the rate of deceleration.

It should be considered that by providing an efficient collector passage, the size of the primary portion of the draft tube may be cut down without serious loss to draft tube efficiency, but with a material reduction in the overall dimensions of the entire draft tube and consequently of the power house and sub-structure.

While the various forms of the invention have been shown as applied to turbines having vertical shafts, it is obvious that with slight modification of structure it is applicable to turbines having horizontal shafts as shown in the prior forms. There has been shown a draft tube and a spreading collector which receives the flow in an axial direction and discharges it in a radial direction, that is, along a plane at substantially right angles to the axis of the draft tube. It is to be understood that with any of the forms the angle between the entrance passage axis and the discharge direction need not necessarily be exactly a right angle as conditions of practice make it desirable to increase or decrease this angle somewhat.

While in the foregoing description a distinction has been made between the primary draft tube and the transition and collector passages, it will be recognized that the primary draft tube and transition and collector passage functions may with certain constructions be so merged that no one portion of the structure may be termed a primary draft tube and the remainder a collector. Such instances may nevertheless fall within the scope of the present invention as set forth in the appended claims.

This application is a continuation in part of my copending application Serial No. 195,105 filed May 28, 1927, and is directed to the improved draft tube.

I claim:

1. A draft tube having angularly disposed

- entrance and discharge passages, the central axes of which are relatively offset, while the upstream wall of said discharge passage lies near the outlet of said entrance passage and is so formed that the draft tube is of the general elbow type, said entrance passage being adapted to conduct a solid column of water throughout and having at its outlet a crest which is disposed substantially a uniform distance from the beginning of said entrance passage.
2. A draft tube having angularly disposed, relatively offset entrance and discharge passages, which in at least one section thereof comprise inner and outer walls forming a draft tube of general elbow formation wherein substantially the entire fluid flows in a downstream direction from the entrance passage into said discharge passage, the fluid flow in said entrance passage being in a solid column formation throughout its length.
3. A draft tube having an entrance passage, terminating in a bell-mouth, and an angularly disposed passage offset relatively thereto, said passages in at least one section having inner and outer curved surfaces forming the outline of an elbow-type of draft tube.
4. A draft tube having an entrance passage, terminating in a bell-mouth, and an angularly disposed passage offset relatively thereto, said passages in at least one section having inner and outer curved surfaces forming the outline of an elbow-type of draft tube and having their centers of curvature on the downstream side of the central axis of the entrance passage.
5. A draft tube having an entrance passage provided with a bell-mouth, and an angularly disposed passage offset relatively thereto, said passages in at least one section having inner and outer curved surfaces forming the outline of an elbow-type of draft tube and having their centers of curvature on the downstream side of the central axis of the entrance passage, the radius of curvature of the inner surface being less than that of the outer surface.
6. A draft tube having an entrance passage provided with a bell-mouth, and an angularly disposed passage offset relatively thereto, said passages in at least one section having inner and outer curved surfaces forming the outline of an elbow-type of draft tube and having their centers of curvature on the downstream side of said inner surface.
7. A draft tube having an entrance passage provided with an outwardly flaring bell-mouth, and a horizontal passage having a transition passage the upstream wall of which intersects the upstream side of said bell-mouth, said entrance and transition passages being relatively eccentrically disposed.
8. A draft tube having an entrance passage terminating in an outwardly flaring bell-mouth which is formed as a surface of revolution, and an angularly disposed passage for conducting the flow from said entrance passage and eccentrically disposed relatively thereto, said angular passage having an upstream wall which in at least one section curves everywhere in a downstream direction from a point adjacent to the uppermost portion of said bell-mouth.
9. A draft tube having an entrance passage terminating in an outwardly flaring bell-mouth which has a surface of revolution as its basis, and an angularly disposed passage having an upstream wall which is everywhere curved in a downstream direction from a point adjacent to the uppermost portion of said bell-mouth.
10. A draft tube having an entrance passage terminating in an outwardly flaring bell-mouth which has a surface of revolution as its basis, and an angularly disposed passage having an upstream wall which is everywhere curved in a downstream direction from a point adjacent to the uppermost portion of said bell-mouth, whereby said curving wall intersects the upstream portion of said bell mouth so as to foreshorten the upstream portion of the latter in both a lateral and horizontal direction.
11. A draft tube having an entrance passage terminating in a bell-mouth, and an angularly disposed passage, the upstream wall of said angular passage gradually curving upwardly and meeting the upstream wall of said entrance passage at a point adjacent to the upper portion of said bell-mouth.
12. A draft tube having an entrance passage terminating in a bell-mouth, and an angularly disposed passage, the upstream wall of said angular passage curving upwardly and meeting the upstream wall of said entrance passage at a point adjacent to the upstream portion of said bell-mouth, the upstream wall of said angular passage having the same degree of curvature when cut by parallel planes.
13. A draft tube having an entrance passage terminating in a bell-mouth, and an angularly disposed passage, the upstream wall of said angular passage curving upwardly and meeting the upstream wall of said entrance passage at a point adjacent to the upstream portion of said bell-mouth, the upstream wall of which has the same degree of curvature when cut by parallel planes which are also disposed parallel to the axes of said entrance and angular passages.
14. A draft tube having an entrance passage terminating in a bell-mouth, and an angularly disposed passage, the upstream wall of which curves upwardly and meets the upstream wall of said entrance passage at a point adjacent to the upstream portion of

said bell-mouth, the upstream wall of said angular passage having in horizontal section a greater degree of curvature along one side of its center line than on the other side thereof.

15. A draft tube having an entrance passage, and a passage disposed angularly thereto and provided with an upstream wall, so shaped that when cut by a series of vertical parallel planes each section so formed will have the same degree of curvature as all other sections.

16. A draft tube having an entrance passage, and a passage disposed angularly thereto and provided with an upstream wall so shaped that when cut by a series of planes parallel to each other and to the central axes of said passages each section so formed will have the same degree of curvature as all other sections.

17. A draft tube having an entrance passage, and an angularly disposed passage having side walls and an upstream wall which, in horizontal section and from a point adjacent to the upstream side of said entrance passage, curves in a relatively gradual curve to one of said sides, and in a relatively sharper curve to the other of said sides.

18. A draft tube having an entrance passage, and an angularly disposed passage having side walls and an upstream wall which in horizontal section curves, from a point adjacent to the upstream side of said entrance passage, in a relatively gradual curve to one of said sides, and in a relatively sharper curve to the other of said sides, said upstream wall being formed by radii disposed in parallel planes.

19. A draft tube having an entrance passage, and an angularly disposed passage having side walls and an upstream wall which in horizontal section curves, from a point adjacent to the upstream side of said entrance passage, in a relatively gradual curve to one of said sides, and in a relatively sharper curve to the other of said sides, said upstream wall being formed by radii disposed in planes parallel to said sides.

20. A draft tube comprising an entrance passage, and an angularly disposed passage having an upstream wall formed by a series of radii of identical length, the locus for the radii centers being a line disposed in a horizontal plane and shaped similarly to the back of said upstream wall in a horizontal section.

21. A draft tube having an entrance passage, and an angularly disposed passage offset with respect thereto and provided with a roof which in transverse section is inclined upwardly toward the side of said angular passage most remote from the central axis of said entrance passage.

22. A draft tube having an entrance passage, and an angularly disposed discharge

passage offset with respect thereto and provided with a roof which in transverse section is inclined upwardly toward the side of said angular passage most remote from the central axis of said entrance passage, and a central pier disposed in said discharge passage.

23. A draft tube having an entrance passage, and an angularly disposed passage offset with respect thereto and provided with a roof which in transverse section is inclined upwardly toward the side of said angular passage most remote from the central axis of said entrance passage, and a pier disposed in said discharge passage at the central portion thereof.

24. A draft tube having an entrance passage, and an angularly disposed passage offset with respect thereto, and having a roof inclined upwardly in a downstream direction and one side only of which is inclined upwardly in a transverse direction.

25. A draft tube having an entrance passage, and an angularly disposed passage offset with respect thereto, and having a roof inclined upwardly in a downstream direction and one side only of which is inclined upwardly in a transverse direction, said transverse inclination being on the greater offset side of said passage.

26. A draft tube having an entrance passage, and an angularly disposed passage provided with floor and roof surfaces relatively diverging in a downstream direction, while in a transverse direction said roof is inclined upwardly along only one side thereof.

27. A draft tube having an entrance passage, and an angularly disposed passage provided with floor and roof surfaces relatively diverging in a downstream direction, while in a transverse direction said roof is inclined upwardly along only one side thereof, the degree of said transverse inclination decreasing in an upstream direction.

28. A draft tube having an entrance passage, and an angularly disposed passage provided with floor and roof surfaces relatively diverging in a downstream direction, while in a transverse direction said roof is inclined upwardly along only one side thereof, the upstream wall of said angular passage being formed by a series of parallel radii.

29. A draft tube having an entrance passage, and an angularly disposed discharge passage offset with respect thereto, said entrance passage being provided with a flaring bell mouth formed on the basis of a surface of revolution while said discharge passage has an upstream wall intersecting said bell mouth thereby shortening the same on the upstream side thereof whereby in at least one section said upstream wall forms substantially a continuation of the upstream side of said entrance passage thereby forming a draft tube of the general elbow type wherein fluid flows from said entrance passage into said

discharge passage substantially entirely in the downstream direction.

30. A draft tube having an entrance passage, and a passage disposed angularly thereto and provided with an upstream wall so shaped that when cut by a series of vertical parallel planes each section so formed will have the same degree of curvature as all other sections, and which upstream wall in horizontal section curves from a point adjacent the intermediate portion thereof.

31. A draft tube having an entrance passage, and a passage disposed angularly thereto and provided with an upstream wall so shaped that when cut by a series of planes parallel to each other and to the central axes of said passages each section so formed will have the same degree of curvature as all other sections, and which upstream wall in horizontal section curves starting from a point intermediate the sides of said angularly disposed passage.

32. A draft tube having an entrance passage, and a passage disposed angularly thereto and provided with an upstream wall, said wall being so shaped that when cut by vertical parallel planes the sections formed thereby have substantially the same general contour and said upstream wall when cut by parallel horizontal planes the sections formed thereby also have substantially the same general contour.
